UNITED STATES PATENT OFFICE.

WILLIAM G. JEFFREY, OF READING, MASSACHUSETTS.

REED-ORGAN PIPE.

1,359,897.

Specification of Letters Patent. Patented Nov. 23, 1920.

Application filed June 8, 1920. Serial No. 387,372.

To all whom it may concern:

Be it known that I, WILLIAM G. JEFFREY, a citizen of the United States, residing at Reading, in the county of Middlesex and 5 State of Massachusetts, have invented new and useful Improvements in Reed-Organ Pipes, of which the following is a specification.

This invention relates to that portion of a 10 reed organ pipe known as the block, and interposed between the usual fixed socket, forming a portion of the boot, and the usual resonant pipe above the boot, constituting a portion of the resonator, the block being 15 adapted to hold the usual eschalot and the tuning wire coöperating with the reed of the eschalot.

The object of the invention is to provide 20 a block of improved construction, whereby the cost of manufacture is decreased and the strength, durability and effectiveness of the block are increased as compared with the construction heretofore employed, my improved block constituting in one piece the 25 usual eschalot holder and a portion of the resonator.

The invention is embodied in the improvements which I will now proceed to describe and claim.

30 Of the accompanying drawings forming a part of this specification,—

Figure 1 is a side elevation, showing a 35 block embodying the invention, the usual eschalot and tuning wire, a portion of the fixed socket, and a portion of the resonant pipe, the socket and a portion of the resonant pipe being shown in section.

Fig. 2 is an elevation showing the same 40 parts, and taken from a different point, the fixed socket being omitted.

Fig. 3 is a section on line 3—3 of Fig. 1, the fixed socket being omitted.

Fig. 4 is a bottom plan view of the structure shown by Figs. 1 and 2.

45 Fig. 5 is a section on line 5—5 of Fig. 2, looking upward.

Fig. 6 is a section on line 6—6 of Fig. 3, the eschalot and resonant pipe being omitted.

Fig. 7 is a section on line 7—7 of Fig. 2, 50 omitting the eschalot and the resonant pipe.

Fig. 8 is a section on line 8—8 of Fig. 2, looking downward.

The same reference characters indicate 55 the same parts in all of the figures.

In the drawings, 12 represents the usual

fixed socket constituting a portion of the boot of a reed organ pipe, and 13 represents the usual resonant pipe in alinement with the socket 12, and spaced above the same, said pipe constituting a portion of the resonator. 60

In carrying out my invention, I provide as a connection between the socket 12 and pipe 13, a one-piece block cast in a mold from a suitable metallic alloy, said block being longitudinally elongated to occupy the space 65 between the socket 12 and the pipe 13, and provided with a longitudinal bore, which includes a lower portion 14, and an upper portion 15, which is tapered as shown by Figs. 3, 6 and 7.

70 My improved elongated block is composed of a lower end portion 17, formed to hold the eschalot 19, and to enter the upper end of the socket 12, a cylindrical upper end portion 30, formed to enter the lower end of the resonant pipe 13, and an enlarged intermediate portion 26, having a lower annular shoulder 18, formed to be seated on the upper end of the socket, and an upper annular shoulder 29, formed as a seat for the lower 80 end of the resonant pipe 13. The bore portion 15 is so tapered that its larger end is within the resonant pipe 13.

85 The intermediate portion 26 is reduced at one side between the shoulders 18 and 29 to form a recess 27, receiving the handle portion of the usual tuning-wire 21. Said recess has an inclined face separated from the tapered bore portion by a relatively thin 90 wall, while the remainder of the intermediate portion, indicated by the reference numeral 28, in Figs. 3 and 8, is relatively thick, to impart adequate strength and resistance to strains tending to bend the elongated block. The intermediate and upper end 95 portions 26 and 30 constitute portions of a resonator which is completed by the resonant pipe 13.

100 The eschalot 19 is held in the bore portion 14, as usual, by a wedge-shaped key 24, inserted in a key-way or slot 23. The tuning-wire passes, as usual, through a guide 20 in the block.

105 When the resonant pipe 13 is made of metal, it may be held in engagement with the upper end portion 30 of the block wholly by friction. When the pipe 13 is made of metal, it may be additionally secured by solder. The construction described, however, permits the employment of a resonant 110

pipe 13, made of non-metallic material, such as vulcanized fiber, in which case the pipe 13 is secured without the use of solder.

The one-piece block constituting a portion 5 of the resonator, provides a strong, durable and effective connection between the socket 12 and the pipe 13, and reduces to a minimum the time and labor involved in constructing the said connection, without impairing or 10 affecting the tone.

Owing to the fact that the portions 17, 26 and 30 constituting my improved block are cast as one piece in a suitable mold, absolute uniformity of the form of all of the 15 blocks made in a given mold is insured, all liability of imperfect formation of any block, due to carelessness of workmanship, being eliminated.

I claim:—

20 In a reed organ pipe which includes a boot and a resonator; a one-piece elongated block having a longitudinal bore, and composed of a lower end portion formed to hold an

eschalot, and adapted to enter the upper end of a socket, a cylindrical upper end portion 25 formed to enter the lower end of a resonant pipe, and an enlarged intermediate portion having a lower annular shoulder formed to be seated on the upper end of the socket, and an upper annular shoulder formed as 30 a seat for the lower end of the resonant pipe; the said upper end and intermediate portions and the resonant pipe constituting the resonator; the said bore being tapered within the intermediate and upper end portions, 35 so that its larger end is within the resonant pipe; the intermediate portion being reduced at one side between said shoulders, to form a tuning-wire-receiving recess, separated from the tapered bore portion by a relatively 40 thin wall; while the remainder of the intermediate portion is relatively thick, to impart adequate strength.

In testimony whereof I have affixed my signature.

WILLIAM G. JEFFREY.
